UNITED STATES PATENT OFFICE

HERMAN COHN, OF BALTIMORE, MARYLAND

GARMENT CLASP

Application filed July 22, 1931. Serial No. 552,527.

This invention relates to necktie and soft collar clasps, and has for its object to provide clasps of this kind with ball bearings to facilitate the entering of the necktie or collar fabric between the opposed jaws of the clasps, and at the same time serve to maintain the collar or tie in fixed relation to other garments of the wearer.

Other objects of the invention will become apparent as the detailed description thereof proceeds.

In the drawings:

Figure 1 is a perspective view illustrating the appearance of the novel clasps in use; 15 Figure 2 is a plan view of one form of collar holder, parts thereof being broken away to show details of construction;

Figure 3 is a rear elevation of the holder shown in Figure 2, part being broken away 20 to show details of construction;

Figure 4 is a fragmentary sectional detail of a modified form of the invention;

Figure 5 is a section of another modification;

25 Figure 6 is a side elevation of a clasp used to clamp a tie front resiliently to other garments of the wearer, parts being broken away to show details of the gripping elements of the clasp;

30 Figure 7 is a side elevation similar to Figure 1, but showing a modified form of the invention; and

Figure 8 is a plan view of the tie clasp illustrated in Figure 7.

35 The collar holder shown in Figures 2 and 3 of the drawings comprises a curved member 1 which may be suitably ornamented on its surface and which forms the foundation support for a member 2 of substantially the same 40 length as the member 1. A sleeve 3 is fixed centrally of the member 1 and has two parts 4 and 5 bent over the center of the member 2 to clamp the said member 2 securely to the member 1.

45 The member 2 is preferably made of springy material and extends in opposite directions from a sleeve 3 to form gripping jaws co-operating with the ends of the member 1 to hold the end of a soft collar or other fabric securely between said jaws. The outer

arms 6 and 7 of the member 2 are provided with sockets 8 and 9, respectively, in which are located the balls 10 and 11'. Immediately opposite the ball 10 and centrally arranged on opposite sides of the ball 10 are 55 balls 11 and 12 suitably secured for rotation in every direction in sockets 13 and 14 formed on the outer left hand end of the member 1. Similarly, balls 15 and 16 are secured in sockets 17 and 18 formed on the inner face 60 of the right hand end of the curved member 1 and on opposite sides of the ball 11'.

The spacing of the balls 11 and 12 relative to the ball 10 forms a depression adapted to hold a tab 19 of a collar 20 with a yielding 65 friction grip. While this arrangement of ball bearing permits a comparatively free sliding movement of the collar holder, shown in Figure 2, the depression formed between these balls also serve to depress the fabric 70 into the recess formed there and to hold the tab 19 securely. The ball 11' and balls 15 and 16 on the other side of the collar holder 8 perform a like function on the tab 21 of the collar 20.

75 The modification shown in Figure 4 of the drawing discloses the construction in which a single ball bearing is used on opposite jaws of a collar holder to clasp the tabs of a collar therebetween. In this form of the invention a stiff base member 22 is provided with the sleeve 23 similar in function to the sleeve 3, shown in Figure 2. The outer end of the member 22 is provided with a ball 24 seated in the usual socket 25. The opposite 80 end of the member 26 is provided with a socket 27 in which a ball 28 is suitably secured to co-operate with the ball 24 in holding the tab of a collar or other fabric securely 85 between the aforesaid jaws. It will be evident from this construction that while the fabric 29 may be free to move without tearing between the balls 24 and 28 in all directions, that the bend in the fabric will serve as a 90 sort of yielding lock to hold the fabric properly positioned in the holder.

95 In the modification, shown in Figure 5, the members 30 and 31 corresponding to the members 1 and 7 of Figure 2 of the drawing, are provided with oppositely disposed sockets 32 100

and 33, respectively, in which are mounted balls 34 and 35 for the same purpose as in the other modification. In this case, however, the balls of different size have a sort of differential movement which tends to impose a greater friction grip on the fabric between them than would be the case if the balls were of equal size.

In Figure 6 there is shown a tie clasp designated generally by the reference numeral 36. This clip comprises a lower member 37 connected by a bend 38 to the upper member 39. The upper member has a socket 40 formed near its outer end to receive the ball bearing 41. The lower member 37 has a socket 42 formed directly opposite the socket 40 to receive a smaller ball 43. These balls perform the same function as those shown in Figure 5, in connection with a collar holder. In the modification shown in Figures 7 and 8, the tie clasp is made of a single piece of wire doubled to form a base member 44 consisting of two lengths of wire in contact with each other throughout their length. This double wire base member 44 is bent upwardly at 44' to form an upper member 45 having the upper lengths of wire spread apart to form branches 46 and 47 which are bent inwardly toward and soldered or otherwise secured to each other at their ends remote from bend 44' to form a flat plate-like terminal 48. The lower member 44 at its outer end is provided with spaced apart sockets 49 and 50 in which are seated ball bearings 51 and 52. The upper flat terminal 48 is provided on its under side with a socket 53 in which the ball bearing 54 is mounted; this ball bearing 54 is centered between the balls 51 and 52 so as to form a depression in the tie clamped between the members 42 and 45. The operation of this form of the invention will be apparent from the drawing.

It must be understood that at least one of the members forming the collar or tie clasp will be made of springy material so as to insure a proper gripping contact between the jaws of the clasp at all times. It will also be understood that where the clasp is of sufficient size to permit it, the sockets of each ball bearing will be made deep enough to receive a small compression spring adapted to hold the ball yieldingly in contact with the inwardly curved outer end of the socket. This modification will, of course, provide for different thicknesses of material to be gripped between the gripping members of the collar holder and tie clasps, and will always insure these garments being properly clipped by the clasps.

While I have shown the invention as embodied in several different concrete forms it is to be understood that these forms may be varied without departing from the spirit of the invention, the scope of which is outlined in the claims annexed hereto.

What I claim is:

1. A necktie holder formed of a length of resilient wire folded on itself to form opposed gripping jaws, ball bearings spaced apart on one of said jaws and near the end thereof, and a ball bearing on the other jaw in yielding gripping contact with said bearings. 70

2. A necktie holder formed of a length of resilient material folded on itself to form substantially parallel opposed gripping members, a ball bearing mounted near the end of one of said members, and a ball bearing member mounted on the end of the other member in position to contact with the ball bearing 80 on the first member. 75

3. In a soft collar holder, a base member, a second member secured to said base member between the ends thereof and bent to form jaws on opposite sides of the connection and co-operating with the ends of said base member, and ball bearings mounted near the ends of said members and normally in garment gripping contact with each other. 85

4. A garment clasp comprising a pair of members connected to each other to form relatively resilient jaws having their opposed ends normally closed adjacent to each other, and ball bearings laterally offset from each other and mounted in said ends to rotate in 95 all directions in contact with a garment inserted between said jaws. 90

5. A garment clasp comprising a pair of members connected to each other to form relatively resilient jaws having their opposed ends normally closely adjacent to each other, and ball bearings mounted in said ends to rotate in all directions in contact with a garment inserted between said jaws. 100

In testimony whereof I affix my signature. 105
HERMAN COHN.
